Attorney

UNITED STATES PATENT OFFICE.

ROBERT RUFFIN, JR., OF SENATOBIA, MISSISSIPPI.

DRAFTING INSTRUMENT.

Application filed June 21, 1922. Serial No. 569,838.

To all whom it may concern:

Be it known that I, ROBERT RUFFIN, Jr., a citizen of the United States, residing at Senatobia, in the county of Tate and State 5 of Mississippi, have invented a new and useful Drafting Instrument, of which the following is a specification.

This invention aims to provide a simple means whereby cross sections in earth work 10 may be platted readily from field notes.

It is within the province of the disclosure to improve generally and to enhance the utility of devices of that sort to which the invention appertains.

15 Although a preferred embodiment of the invention is depicted in the drawings, and hereinafter described, it will be understood that an instrument maker, working within the scope of what is claimed, may alter the 20 structure shown, as to its precise form, without departing from the spirit of the invention or avoiding the charge of infringement.

In the drawings:—

Figure 1 shows in plan, an instrument 25 constructed in accordance with the invention: Figure 2 is a view showing a sample of the field notes to be platted.

The instrument forming the subject matter of this application is fashioned from 30 celluloid, paper, metal or any other thin material and embodies a frame 1, including a top strip 2, a bottom strip 3, end members 4 connecting the strips, an intermediate rib 5 connecting the strips, lateral ribs 6, 7 and 35 8 connecting the strips, and located at one side of the intermediate rib 5, and lateral ribs 9 connecting the strips and located on the opposite side of the rib 5 from the ribs 6, 7 and 8. The top strip 2 has an inner 40 fiducial edge 10, the ribs 9, 5, 6, 7 and 8 being spaced apart and being located at right angles to the fiducial edge 10. The top strip 2 is calibrated as at 11, in opposite directions, from a zero point 12 alined with 45 a longitudinal slot 14 formed in the intermediate rib 5, the rib 5 being calibrated on opposite sides of the slot, and the ribs 6, 7, 8 and 9, together with the end members 4 being calibrated, likewise, as shown at 15, 50 from a zero point indicated at 16 and coinciding with the fiducial edge 10 of the top strip 2. The bottom strip 3 may be calibrated in opposite directions, as at 17, from a zero point 18 alined with the slot 14 in 55 the intermediate rib 5. The bottom strip 3 has an inner fiducial edge 19, which, cooper-

ating with the slot 14 in the rib 5, defines a center 21 from which radiate protractor marks 20 located on the top strip 2 and the end members 4. A few of the protractor marks 20, only, are shown, for the sake of clearness, but there may be as many of them as is considered expedient. The protractor marks afford, obviously, a means whereby angles may be laid off with the edge 19 of 65 the bottom strip 3 as a line of reference.

In Figure 2 there is shown a set of field notes which, let it be supposed, are to be platted. The column 22 is for the stations. The plus rod readings are entered in the 70 column 23. The column 24 is adapted to receive the minus rod readings. The height of the instrument is entered in column 25. The elevation of the various points is noted in column 26. Column 27 is for the elevation 75 of the grade line. The cut may be marked in column 28 and the fill in column 29. The notes above alluded to are for illustration, merely, the engineer keeping his notes in such form as his taste may dictate.

The device forming the subject matter of this application is adapted to be used in connection with cross section paper, for laying out a line representing the contour of the ground at any cross section in earth work. 85 The slot 14 in the rib 5 is made to coincide with any line on the cross section paper which has been selected to represent the vertical central line of the cross section. The fiducial edge 10 or the strip 2 is brought into 90 coincidence with the line on the cross section paper which has been fixed upon as representing the height of the instrument. Suppose that the operator intends to plat the cross section at station 17 noted in 95 column 22 of the notes. At the center line of the cross section at this station there is a minus rod reading of 6.5, as shown in column 24. This distance is read off on one of the scales of the intermediate rib 5, and a 100 dot is made at the proper place on the cross section paper, through the slot 14. Suppose that the next rod reading was taken at a distance of five feet to the right, as shown in column 22. This distance is read off to the right on the scale 11, and the minus rod reading of 7.5 is read off on the scale of the rib 6, a dot being made on the cross section paper at the proper place. In the same way, 105 a minus rod reading of 8.0 at ten feet to the right of the traverse may be read off from the scale on the rib 7, and a mark made 110

on the paper. In the same way, the rod readings to the left of the traverse may be platted by means of the scales on the ribs 9. After the rod readings have been entered 5 properly on the paper, as above described, the dots on the paper may be connected by a line indicating the contour of the ground, and after the shape of the earth prism has been fixed and laid down, the cross sectional 10 area may be taken off by means of a planimeter, or in any other way.

If the cuts are given, as indicated in column 28, instead of the rod readings, the fiducial edge 10 of the top strip 2 is set at 15 the grade line on the paper, shown by the entry in column 27 of the notes, and, then, the cuts, indicated in column 28, are platted as hereinbefore described in connection with the rod readings.

20 I claim:—

1. An instrument for plating cross sections in earth work, comprising a frame including top and bottom strips, an intermediate rib connecting the strips, and lateral 25 ribs connecting the strips and located on opposite sides of the intermediate rib, one of the strips having an inner fiducial edge, the ribs being spaced apart and being located

at right angles to the fiducial edge, one of the strips being calibrated in opposite directions from a zero point coinciding with the intermediate rib, all of the ribs being calibrated longitudinally from a zero point coinciding with the fiducial edge. 30

2. An instrument for plating cross sections in earth work, comprising a frame including top and bottom strips, an intermediate rib connecting the strips, and lateral ribs connecting the strips and located on opposite sides of the intermediate rib, the 35 intermediate rib having a longitudinal slot, the top strip having an inner fiducial edge, the ribs being spaced apart and being located at right angles to the fiducial edge, the top strip being calibrated in opposite 40 directions from a zero point coinciding with the slot, and all of the ribs being calibrated longitudinally from a zero point coinciding with the fiducial edge. 45

In testimony that I claim the foregoing 50 as my own, I have hereto affixed my signature in the presence of two witnesses.

ROBERT RUFFIN, Jr.
